UNITED STATES PATENT OFFICE.

WILLIAM E. WALSH, OF LOWELL, MASSACHUSETTS, ASSIGNOR TO DRAPER CORPORATION, OF HOPEDALE, MASSACHUSETTS, A CORPORATION OF MAINE.

SPINNING OR WINDING MACHINE.

1,301,022.

Specification of Letters Patent. Patented Apr. 15, 1919.

Application filed July 22, 1918. Serial No. 245,978.

To all whom it may concern:

Be it known that I, WILLIAM E. WALSH, a citizen of the United States, residing at Lowell, in the county of Middlesex and 5 State of Massachusetts, have invented an Improvement in Spinning or Winding Machines, of which the following description, in connection with the accompanying drawings, is a specification, like characters on the 10 drawings representing like parts.

The invention to be hereinafter described relates to spinning or winding machines, and more particularly to the builder mechanism for winding yarn on the receivers or bobbins 15 to be subsequently used as the filling or weft, during the weaving of cloth.

In looms of the feeler type, wherein the filling is replenished prior to complete exhaustion, it is usual to provide a reserve supply of filling on the bobbins or other receivers, to prevent partial or mispicks after a call 20 for replenishment. Many devices have been devised for placing this reserve supply of filling or "bunch" as it is sometimes called, 25 on the bobbins or receivers during the spinning operation; and one of the objects of the present invention is to provide a mechanism of this general character which shall be simple in construction and effective in operation. Economic reasons dictate that the 30 reserve supply of filling remaining on the bobbin or receiver when it is ejected and a new supply is furnished, shall be as small as possible consistent with proper regard for mis- 35 picks or partial picks and tension of filling. One of the purposes of the present invention, therefore, is to provide a mechanism which will place upon the bobbins or receivers, reserve supply of filling or "primary 40 windings", as they may be called, which shall be sufficient in amount to prevent partial or mispicks, and furnish sufficient tension, and yet shall cause minimum waste when the bobbins or receivers are ejected 45 from the loom.

When the bobbins or receivers are of the slotted type for the entrance of the feeler when the filling has been substantially exhausted, it is desirable that the reserve supply 50 of filling or primary windings may be

located at or beyond one end of the slot in the bobbins or receivers, and that such slot may be covered by sufficient windings of 55 yarn or thread to prevent entrance of the feeler or actuation of the replenishing mechanism until the filling has reached the desired state of exhaustion. An important feature of the present invention, therefore, 60 consists in means for placing at one end of the slot of such slotted bobbins or receivers, the reserve supply of filling, and to cover the slot by a service winding which is placed 65 upon the bobbins or receivers immediately upon the completion of the reserve supply or primary windings. In carrying this feature of the invention into effect, the reserve supply or preliminary windings are preferably placed adjacent the base or head of the bobbins or receivers by an upward and a downward short traverse of the yarn or 70 thread, and then a full service traverse to cover the slot in the bobbins or receivers.

The invention will be described in connection with a worsted spinning machine, but it is to be understood that it is not limited 75 thereto, and may be adapted for use in any character of spinning or winding machines.

In the drawings:

Figure 1 is a side elevation of sufficient portions of a worsted spinning machine with 80 the present invention associated therewith, to make clear the construction and mode of operation;

Fig. 2 is a detached detail of a sliding plate for controlling the datum stop; 85

Fig. 3 is a cross section on the line 3—3 of Fig. 2;

Fig. 3^a is a side elevation of a slotted bobbin having the preliminary windings and a first layer of service windings; 90

Fig. 4 is an enlarged detail showing the auxiliary cam, the plunger and locking device;

Fig. 5 is a plan view of the parts shown by Fig. 4;

Fig. 6 is a section on the line 6—6 of Fig. 5, showing the condition of parts after a single upward traverse of the preliminary windings;

Fig. 7 is a similar view, showing the rela- 100

tion of parts in full lines after the completing of the preliminary windings, and commencement of the service windings; and Fig. 8 is a detached detail in end elevation, 5 parts being shown in section, more particularly illustrating the manner of operating the locking device.

The main supporting frame of the machine may be of any desired construction, 10 and as shown in the present instance, comprises the end frames 1, connected by the longitudinal rails 2 and 3, the latter of which may constitute the usual spindle supporting rail of the worsted spinning machine. 15 Mounted on the spindle-rail 3 are a series of spindles 4 of any appropriate number, which extend upwardly through a way-plate or lifting rail 5. Each of the spindles 4 is adapted to support the yarn receiver or 20 bobbin 6 which extends upwardly into the caps 7, (Fig. 1) mounted as usual upon the top portion of the respective spindles 4 or supported in any other desired or suitable manner, the lower edge portion of the cap 25 7 constituting yarn guides for directing the yarn to the bobbins or receivers. As usual in worsted spinning machines, the bobbins are suitably rotated for spinning and winding the yarn.

30 Suitably mounted on the machine frame is the cam shaft 8 having secured thereto for rotative movement the cam 9 which shall constitute the usual builder cam. Pivotaly mounted on the machine frame at 10 is the swinging arm 11 carrying the roller 12 which bears upon the cam 9. Pivotaly mounted at the lower portion of the machine as at 13, is the arm 14 which may be of the usual construction, and on the arm 14 is the 35 bracket 15 carrying the roller 16 which bears upon the plate face 17 of the swinging arm 11, whereby the swinging movement of the arm 11 may be transmitted to the arm 14. The bracket 15 has connected thereto the 40 rack 18 which engages a pinion 19 connected to the rotating shaft 20, the latter being operated as usual in this class of machines, from suitable power through the train of gearing 21, 22. Connected to the shaft 20 45 and the arm 14 is the traverse screw 23 which transmits traverse motion from the cam-operated swinging arm 11 to the traverse slide 24 during the service traverse. The parts thus far described may be of usual construction employed in worsted spinning machines, and since they are well understood by those skilled in the art, further detailed description thereof is unnecessary.

The traverse rod 24 has connected thereto 50 the chain or other flexible connection 25 secured to the projection 26 at the lower portion of the lifter rods 27, the upper ends of the latter being connected to the way plate or lifter rail 5, the construction being such

that traverse movement imparted to the traverse rod 24 is transmitted to the way-plate 5 to raise and lower the same. The chain or connection 25 between the traverse rod and projections 26 may be suitably guided upon 70 guide rolls 28, 29, Fig. 1.

Mounted upon the traverse rod 24 is an auxiliary cam 30, the function of which is to impart to the traverse rod suitable short traverse movements to lay upon the filling carriers or bobbins the primary windings. 75 In the present instance, the traverse rod 24 has secured thereto a bracket 31, Figs. 4 and 5, which is provided with a bearing 32 through which extends the auxiliary cam shaft 33. The auxiliary cam 30, in the present instance of the invention, is secured to the cam shaft 33 at one side of the bearing 32 and a collar 34 on the opposite side of said bearing, (see Fig. 5) maintains the cam and the cam shaft in proper related position.

In order that the traverse rod 24 may be properly guided under the weight of the parts carried thereby as will more fully appear, the spindle-rail 3 has secured thereto a bracket 35, Fig. 1, the lower end portion of 90 which is provided with a slotted guide 36, Figs. 1 and 5, through which the cam shaft 33 extends, the construction being such that the slotted guide bracket serves to support and guide the traverse rod 24 in its movements.

Loosely mounted on the cam shaft 33 is a sprocket wheel 37 about which passes the sprocket chain 38. The sprocket chain 38 may be driven from any suitable source of power, but in the present instance of the invention it is connected to a sprocket wheel 39 secured to the shaft 8, said chain passing about suitable guide pulleys 40 and 41 projecting from a bracket 42 extending downwardly from the longitudinal rail 2, Fig. 1, the construction being such that during the operation of the machine, the sprocket wheels 39 and 37 will be continuously rotated.

Secured to the cam shaft 33 is an arm 43 carrying a hand piece 44 and a spring-actuated locking pin 45, Fig. 5, which is adapted to engage any one of a series of openings or recesses 46 in the face of the sprocket wheel 37, thereby locking the cam shaft and perforce, the cam 30, to the sprocket wheel 37, the construction being such that during the operation of the machine the usual builder cam 9 and the auxiliary cam 30 will be continuously operated.

The locking pin 45 may be variously contrived, but in the present instance of the invention, it comprises the pin 45 extending through the hand-piece 44 and having a collar 47, Fig. 5, between which and an adjustable stop 47^x is interposed a spring 48 normally acting to move the pin 45 into locking engagement with one of the openings 46

of the sprocket wheel 37. The outer end portion of the pin 45 is provided with a hand-piece 49, whereby the pin 45 may be disengaged from the ratchet wheel 37 when 5 desired.

Secured to the traverse rod 24 as by the screws 50, Fig. 5, is a bracket 51, see Figs. 5, 10 6 and 7, through which extends a movable member or plunger 52 carrying a roller 53 which is adapted to bear upon the auxiliary 15 cam 30.

As hereinbefore stated, it is desirable to place the primary windings on the bobbins at predetermined portions thereof, and preferably to commence such preliminary windings at the base of the bobbin or adjacent the head thereof, and upon completion of one or more short traverses, to pass at once to the service or long traverse. To this end 20 there is provided a datum stop which determines the traverse of the preliminary windings in an upward direction from the base of the bobbin, and upon completion of one or more of such short or preliminary traverses 25 windings, is automatically moved to an inoperative position to permit service windings or long traverse to be resumed. In the present instance of the invention, the datum stop consists of an arm 54, Fig. 1, adjustably 30 mounted in a sleeve 55 pivotally mounted on a bracket 56 at 57 and held in adjusted position in the sleeve 55 by suitable means such as the nuts 58. The arm 54 carries the stop proper 59, the toe portion 60 of which is 35 adapted to engage the enlarged portion 61 of the plunger or movable member 52 and prevent movement of the plunger to the left, Fig. 1, during the action of the auxiliary cam 30, the construction being such that 40 during the action of the auxiliary cam 30, the traverse rod 24 which carries the cam, will be moved under the dictates of the auxiliary cam to lay the preliminary windings from the base of the bobbin upwardly to the 45 datum point determined by the datum stop, and then downwardly to the base of the bobbin and upwardly again, the traverses during the action of the auxiliary cam 30 being relatively short. When the preliminary 50 windings have been thus laid first in an upward and then in a downward direction to furnish the desired reserve filling, it is desirable that full service traverse shall be at once resumed and the present invention 55 provides means to this end, as will now be described.

The arm 54 of the datum stop has connected thereto a flexible member or cord 62, Fig. 1, which passes about suitable guide rolls 63 60 and has secured thereto a weight 64. Between the weight and the cord 62 is interposed a plate 65 which passes through a slot 67 in a plate 68 and is provided with a pin 66 which normally rests upon the plate 68

above the slot. The slot 67 has an enlarged 65 portion 69, Fig. 2, which, when brought below the pin 66, permits the weight 64 to lift the datum stop from its operative position.

The plate 68 as indicated in Fig. 1, is 70 slidably mounted in suitable ways or guides 70 secured to the rail 2, and is provided with a series of ratchet teeth 71 adapted to be engaged by a pawl 72 carried by the swinging arm 11, the construction being such that during the rotative movement of the cam 9 75 on the shaft 8, the swinging arm 11 and the pawl 72 will be actuated to feed the plate 68 to the right, Fig. 1, and finally bring the enlarged opening 69 of the plate below the pin 66 to permit the latter to pass, and the 80 datum stop to be raised from operative position. The above-described means constitutes a good form of mechanism for the purposes of automatically controlling the time of movement of the datum stop from its operative 85 to its inoperative position, but obviously this means may be variously contrived.

When the datum stop is removed from its operative position, it is desirable that the plunger or movable member 52 be locked to the traverse rod, and various forms of mechanism may suggest themselves for this purpose, but in the present instance of the invention a plate 73 is hinged at 74 to the 90 guide 51 in which the plunger 52 is supported, and said plate 73 is normally under the influence of a spring 75 tending to lift the plate into the position indicated in Fig. 6. Secured to the free end portion of the plate 95 73 by means such as the screw 76, is a leaf 100 spring 77. Rising from the guide 51 are the supporting arms 78 carrying the rock shaft 79 which may be appropriately supported in bearings 80 at the upper portion of the arm 78, see Fig. 8. Extending downwardly from the rock shaft 79 and disposed above the leaf spring 77 is the finger 81, the construction being such that if the finger 81 is moved from the position indicated in Fig. 1 to that indicated in Figs. 6 and 7, it 110 will operate upon the leaf spring 77 to place the plate 73 under a depressing tendency, overpowering the spring 75, so that when the plate 73 is free to be moved downwardly, under the impulse of the spring 77, it will 115 respond thereto. Secured to the rock shaft 79 is an operating member or arm 82 which is adapted to engage a stop 83 secured to the plunger 52, the construction being such that when the parts are in the position indicated 120 in Fig. 1, and the traverse rod 24 is moved to the left by the auxiliary cam 30 in laying the first short preliminary windings, the end portion of the plate 73 previously resting upon the stop 61 of the plunger would take the position as indicated in Fig. 7, thereupon locking the plunger to the traverse rod 24 or preventing movement of

125

the plunger 52 to the right relative to the traverse rod. At this time the auxiliary cam 30 has made one complete rotation from the position indicated in Fig. 1 through the position indicated in Fig. 6, to the position indicated in Fig. 7, and therefrom, further rotation of the auxiliary cam 30 has no effect upon the traverse rod, the head of the plunger 52 resting against the end of the 10 traverse screw 23, and full or service traverse will thereupon be initiated.

In commencing the operation of winding the yarn upon the bobbins or carriers, the attendant, by means of the hand-piece 44 15 and locking device carried thereby, turns the cam shaft to position the auxiliary cam 30 as indicated in Fig. 1, and then locks the cam to the sprocket wheel 37. The datum stop is then moved to operative position by 20 hand, and the plate 68 adjusted to support the weight 64. The rock shaft 79 is then turned into the position indicated in Fig. 1, the parts related as shown in said figure being then in starting position. As the auxiliary cam 30 is rotated through the described 25 means, it acts upon the plunger 52 and moves the traverse rod 24 to the left, thereby traversing the yarn by short traverses upwardly from the base of the bobbin; and 30 when the cam has reached the position indicated in Fig. 6, having made a half-turn, the arm 82 will have engaged the stop 83 on the plunger and turned the finger 81 from the position indicated in Fig. 1 to that indicated in Fig. 6, thereby placing the leaf 35 spring 77 under tension. When the cam 30 moves from the position indicated in Fig. 6 to that indicated in Fig. 7, it moves the traverse rod 24 to the right, Fig. 1, thereby 40 traversing the yarn downwardly from the datum point fixed by the stop, and the plate 73 locks the plunger 72 through the traverse rod, the end of the plunger 52 at such time resting against the traverse screw 23. Any 45 further rotation of the auxiliary cam 30 obviously has no further effect, and service traverse at once continues upwardly to cover the slot in the bobbins by the service windings.

50 In the present instance of the invention, the auxiliary cam 30 imparts short traverse to the yarn from a point adjacent the head of the bobbin upwardly to the datum point, and then downwardly, at which time the auxiliary cam has made one complete revolution, and thereupon full service windings are resumed by the usual builder cam and swinging arm.

What is claimed is:—

60 1. In a machine of the class described, the combination of the series of spindles, co-operating yarn guiding means, a cam actuated swinging arm for causing relative movement of the spindles and guiding means to

effect a service traverse of yarn upon the 65 bobbins on said spindles, an auxiliary cam, a datum stop to render the cam actuated swinging arm ineffective, and the auxiliary cam effective during the preliminary windings, and means for automatically tripping 70 the stop when the preliminary windings are completed to permit service windings to be laid through the action of the cam actuated swinging arm.

2. In a machine of the class described, 75 the combination of the series of spindles, co-operating yarn guiding means, a cam actuated swinging arm for causing relative movement of the spindles and guiding means, to effect a service traverse of yarn 80 upon the bobbins on said spindles, an auxiliary cam, a datum stop and plunger to render the cam actuated swinging arm ineffective and the auxiliary cam effective during the preliminary windings, and means for 85 automatically tripping the stop when the preliminary windings are completed to permit service windings to be laid through the action of the cam actuated swinging arm.

3. In a machine of the class described, 90 the combination of a series of spindles and co-operating yarn guiding means, a cam actuated swinging arm and traversing means 95 for causing relative service traverse between the guiding means and bobbins on the spindles, an auxiliary cam, means for continuously rotating said cams, and a datum stop acting through the traversing means to render the cam actuated swinging arm ineffective and the auxiliary cam effective during 100 the preliminary windings, and means for tripping the stop when the preliminary windings are completed.

4. In a machine of the class described, 105 the combination of a series of spindles and yarn guiding means, a traverse rod, a cam actuated swinging arm for actuating the rod during service windings, an auxiliary cam for actuating the rod during the preliminary windings, and a datum stop for determining 110 the point of maximum traverse of the rod in one direction during the preliminary windings.

5. In a machine of the class described, 115 the combination of a series of spindles and yarn guiding means, a traverse rod, a cam actuated swinging arm for actuating the rod during service windings, an auxiliary cam for actuating the rod during the preliminary windings, a datum stop, a plunger interposed between the datum stop and auxiliary cam.

6. A builder motion, comprising, in combination, a cam actuated swinging arm, a traverse rod, an auxiliary cam movable with 125 the traverse rod, a removable stop, a plunger interposed between the stop and auxiliary cam, and a lock for securing the plunger to

the traverse rod when the preliminary windings are completed.

7. A builder motion comprising, in combination, a cam actuated swinging arm, a 5 traverse rod, an auxiliary cam movable with the traverse rod, a removable stop, a plunger interposed between the stop and auxiliary cam, means acting automatically to remove the stop from operative relation with the 10 plunger, and means for locking the plunger to the traverse rod during service traverse.

8. A builder motion, comprising, a service traversing cam and an auxiliary cam, means for continuously operating said cams, a 15 traverse rod adapted to be actuated by each of said cams, a datum stop acting to prevent movement of the traverse rod by the service traversing cam while the auxiliary cam is moving said rod during the 20 preliminary windings.

9. A builder motion, comprising, a service traversing cam and an auxiliary cam, means for continuously operating said cams, a 25 traverse rod adapted to be actuated by each of said cams, a datum stop acting to prevent movement of the traverse rod by the service traversing cam while the auxiliary cam is moving said rod during the preliminary windings, and means for tripping 30 the datum stop to render the service traversing cam effective and the auxiliary cam ineffective when the preliminary windings are completed.

10. In a machine of the class described, 35 a builder motion comprising a service and an auxiliary cam, a traverse rod adapted to be actuated separately by either of said cams, a datum stop for rendering the service cam ineffective and determining the 40 starting point of the preliminary windings, and means for moving the datum stop to an inoperative position when the preliminary windings are completed.

11. A builder motion, comprising, in combination, a cam actuated swinging arm, a 45 traverse rod operated thereby, an auxiliary cam mounted on the traverse rod, a datum stop, and a plunger between the datum stop and traverse rod.

50 12. A builder motion, comprising, in combination, a cam actuated swinging arm, a traverse rod, and connections between the arm and rod for giving service traverse to the latter, said connections including a member 55 mounted on and movable relative to the rod, means to lock the movable member to the rod to prevent movement relative thereto, and an auxiliary cam on the rod acting through said movable member before it is 60 locked to the rod to impart short traverse movement to the rod during preliminary windings.

13. In a machine of the character described, the combination of spindles and

yarn guiding means for directing yarn to 65 bobbins on said spindles, a cam actuated swing arm and connections for imparting relative service traverse between the bobbins and yarn guiding means, said connections including a traverse rod, a movable plunger 70 on the rod, and means for locking the plunger to the rod.

14. In a machine of the class described, the combination of a series of spindles, co-operating yarn guiding means, a cam actuated 75 swing arm and traverse rod for causing relative movement between bobbins on the spindles and yarn guiding means to effect a traverse of yarn upon the bobbins, an auxiliary cam for actuating the traverse 80 rod by short traverse movements during preliminary windings, a datum stop co-operating with the auxiliary cam and means acting automatically when the primary windings are completed to remove the datum 85 stop from operative position and permit full service traverse to be resumed.

15. In a machine of the class described, the combination of a series of spindles, co-operating yarn guiding means, a cam actuated 90 swing arm and traverse rod for causing relative movement between bobbins on the spindles and the yarn guiding means to effect a traverse of yarn upon the bobbins, an auxiliary cam and movable plunger on the 95 traverse rod, a datum stop to engage the plunger and determine the point on the bobbins at which the preliminary windings shall commence, and means to remove the datum stop from operative position and lock 100 the movable plunger to the traverse rod.

16. A builder motion, comprising, a cam actuated swinging arm, a traverse rod, an auxiliary cam on the traverse rod and means co-operating with the auxiliary cam during 105 the primary windings to impart a short traverse movement to the traverse rod, and means for causing the traverse rod to resume full service traverse movements under the control of the cam actuated swinging 110 arm when the preliminary windings have been completed.

17. In a machine of the class described, the combination of spindles, yarn guides, and a traverse rod two means for effecting 115 relative traverse of the guides and bobbins on the spindles, one for full service of long traverse and the other for preliminary windings of shorter traverse, said means including two cams one of which is mounted on 120 the traverse rod, and a datum stop co-operating with the said cam to start the preliminary windings at a predetermined point.

18. A builder motion, comprising, in combination, a cam operated swinging arm, a 125 traverse rod, an auxiliary cam mounted on the traverse rod, a plunger on said rod, a datum stop against which the plunger bears

during the preliminary windings, and a lock for locking the plunger from movement relative to the traverse rod when the preliminary windings are completed.

- 5 19. A builder motion, comprising, in combination, a cam operated swinging arm, a traverse rod, an auxiliary cam on said rod, means for rotating said cams, a plunger adapted to bear against the auxiliary cam, 10 a stop against which the plunger bears during preliminary windings to cause the traverse rod to be moved by the auxiliary cam.
- 10 20. A builder motion, comprising, in com-

bination, a cam operated swinging arm, a traverse rod, an auxiliary cam on said rod, 15 means for continually rotating said cams, a plunger adapted to bear against the auxiliary cam, a stop against which the plunger bears during preliminary windings to cause the traverse rod to be moved by the auxiliary cam, means to lock the plunger to the traverse rod when the preliminary windings are completed.

In testimony whereof, I have signed my name to this specification.

WILLIAM E. WALSH.
